UNITED STATES PATENT OFFICE.

ARTHUR ANDERSON, OF IRONWOOD, MICHIGAN.

NAIL AND BOARD PULLER.

935,727.

Specification of Letters Patent. Patented Oct. 5, 1909.

Application filed March 29, 1909. Serial No. 486,309.

To all whom it may concern:

Be it known that I, ARTHUR ANDERSON, a citizen of the United States, residing at Ironwood, in the county of Gogebic and State of Michigan, have invented a new and useful Nail and Board Puller, of which the following is a specification.

My invention relates to means for removing plank sidewalks, flooring, siding and the like, and for removing the nails and spikes therein, and the object is to provide an efficient tool for said purposes.

In the accompanying drawing, Figure 1 is a top view of my device, shown in position for work upon a sidewalk stringer or a joist. Fig. 2 is a side elevation of the device shown in the action of breaking up a sidewalk. Fig. 3 is a section on the line *a—a* in Fig. 1 showing how the claw of the device may be applied as a nail or spike puller, the frame being omitted.

Referring to the drawing by reference numerals, the device involves a frame composed of two cheek-plates 1, 1, spaced apart and secured together by two cross bars 2, 2, on which rotate two rollers 3, both near the base of the frame. Higher up in the frame is retained by a cotter pin 5, a pivot pin 4, on which is fulcrumed a forked lever 6, which 30 may have a wooden handle 7 to give all required leverage without making the device objectionably heavy. The front end of the lever is provided with two upwardly curved claws 8 spaced far enough apart to straddle 35 the regular stringers 9 on which sidewalk planks 10 are spikes. At the junction of said claws is formed a V-shaped notch 12 adapted for engagement with the heads of spikes and nails in pulling them out of either the planks 40 or the stringers, as will be understood by looking at Fig. 3 where the tool is in position for pulling the spike 13. When the lever is thus applied as a spike puller it is removed from the frame by first removing the pin 4.

In Fig. 2 is shown how the lever while in the frame and while the rollers 2 are resting on the stringer, the claws are pushed in under the planks 10 and raise them from the stringer 9, pulling the spikes with them, except if the planks are so decayed as to let the spike heads pull through them, in which event the spikes are pulled out afterward, as in Fig. 3. As fast as the planks are loosened the tool is pushed forward riding with its 55 rollers on the stringers and the frame cheeks guiding at both sides thereof. Of course,

the stringers 9 represent also floor joists where a floor is to be removed, and studding where sheathing or lath is to be removed from a wall, or boards from rafters of a roof etc. 60 For all of the last named purposes the lever may also be used without the wheeled frame to support it, or it may have a support without wheels.

Having thus described the invention, what I claim is:

1. The combination with a frame having two supporting rollers adapted to roll along a timber to hold the frame upright and guiding portions on the frame straddling the 70 timber, of a forked lever fulcrumed in the frame and having its forked portion curved upward and in straddling position to the timber.

2. The combination with a frame having 75 two supporting rollers adapted to roll along a timber to hold the frame upright and guiding portions on the frame straddling the timber, of a forked lever fulcrumed in the frame and having its forked portion curved 80 upward and in straddling position to the timber, said lever being easily detachable from the frame and provided at the junction of the fork with a V-shaped notch for pulling nails and spikes. 85

3. In combination a supporting frame having means for guiding it along a joist or other timber, a lever fulcrumed in the frame and having its shortest end formed with two long claws adapted to straddle the timber 90 and pull or tear therefrom planks, boards and the like nailed across the timber and a front and rear roller supporting the frame.

4. A device for the purposes set forth, the same comprising a lever bifurcated at one 95 end into two arms with intervening space for rafters, studdings, joists and stringers, said arms being curved from its straddling position toward the side of the timber upon which the lever operates, a carriage pivotally 100 supporting the lever and having two rollers supporting it on the timber, and side flanges extending lower than the lower sides of the rollers, to act as guides at the sides of the timber. 105

In testimony whereof I affix my signature, in presence of two witnesses.

ARTHUR ANDERSON.
